Primary Examiner — Cynthia Underwood(74) *Attorney, Agent, or Firm* — Buchanan Ingersoll & Rooney PC(57) **CLAIM**

The ornamental design for a packaging and blank therefor, as shown and described.

DESCRIPTION

FIG. 1 is a plan view of a blank for a packaging showing our new design.

FIG. 2 is a rear elevational view of the packaging showing our new design.

FIG. 3 is a front elevational view thereof.

FIG. 4 is left side elevational view thereof, the other side being a mirror image thereof.

FIG. 5 is a rear plan view of the blank shown in FIG. 1 in a folded configuration; and,

FIG. 6 is a front plan view thereof.

The portions of the design shown in broken lines are for environmental purposes only and form no part of the claimed design.

1 Claim, 6 Drawing Sheets(56)
